WOOD HEEL CONCAVING MACHINES

George Pickford, Beverly, Mass., assignor to United Shoe Machinery Corporation, Flemington, N. J., a corporation of New Jersey

Application January 27, 1955, Serial No. 484,364

34 Claims. (Cl. 12—46)

This invention relates to machines for concaving wood heel blanks and is herein illustrated as embodied in a machine of the general type disclosed in United States Letters Patent No. 2,038,636, granted April 28, 1936, on an application filed in the name of Walter W. Bradbury.

The attaching face or "cup" of a heel formed or concaved by the use of the machine disclosed in said Patent No. 2,038,636 has a longitudinal median portion which, with the exception of its rear end part, is substantially equidistant from the plane of the rim of the attaching face of the heel and is accordingly of uniform depth. In the manufacture of women's shoes it is common practice to "fit" the heel seat portion of the shoe for the reception of a wood heel and this consists in trimming material from the heel seat portion of an attached outsole of the shoe to form a heel seat tab which, in the finished shoe, lies in the concavity of the attaching face of the heel, and to form a pair of heel breast receiving shoulders against which the upper lateral corner portions of the breast of the heel abut. Outsoles of shoes are not of uniform thickness and the heel seat tabs formed upon said outsoles, especially when said outsoles are "fitted" by hand, vary in shape and in addition to being beveled at their lateral margins are frequently beveled rearward from their heel breast lines.

In the finished shoe the rim or edge portion of the attaching face of the covered heel, which portion consists of a planar land of uniform width, should snugly engage and be firmly pressed into the over-lasted counter portion of the shoe in order to insure that the heel shall merge smoothly with the shoe. Moreover, the heel seat tab which, as above stated, lies in the concavity of the attaching face of the heel of the finished shoe, is relied upon substantially to fill the concavity in the attaching face of the heel and thus provide a solid base for the rear end of the shoe upper.

Because of differences in thickness of the outsoles of shoes and differences in the types and shapes of heel seat tabs formed upon said outsoles, said tabs rarely fill up the attaching faces of the heels as they should, with the result that, when the shoe is worn, the heel of the wearer bearing against the heel end of the insole of the shoe, causes the insufficiently supported heel seat of the shoe, which heel seat includes the tab, to drop or sag into the attaching face of the heel. When this condition exists the shoe becomes uncomfortable because the heel portion of the insole is then somewhat deformed due to its dropping into the unfilled portion or concavity of the attaching face of the heel, thus tending, especially in shoes having high heels, to cause the heel end of the shoe to lose its shape and to become somewhat unstable under pressure of the heel of the wearer.

With the foregoing and other drawbacks, for example imperfect wood heel nailing conditions and breakage of heels due to the fact that the heel seat tabs fail sufficiently to fill the attaching faces of the heels, in view there have been proposed constructions in which the heel seat por-

2

tions of the outsoles of shoes are especially trimmed to register in interfitting relation with especially prepared cavities in the attaching faces of the heels. None of such constructions, however, has been found to be commercially practicable because of the expense involved in forming these prepared cavities and also because the operators fail to exercise the proper care necessary in the fitting of the heel seat tab for registry in these cavities.

It is an object of the present invention to provide a heel blank concaving machine adapted quickly and effectively to form heels having attaching faces provided with planar marginal lands which are of uniform width and having concavities which are defined by said lands and which are of decreasing depth rearwardly from their breast edges. It is another object of the present invention to provide a machine in which the depths of the concavities formed in the attaching faces of the heels may be readily varied and in which the rate at which the concavities decrease in depth as they extend rearward from the breast edges of the heels may be varied.

With the above objects in view I have provided a concaving machine comprising a support having a substantially planar face, a rotary cutter having peripheral cutting edges, a locus of which extends beyond said face, a gage, means for effecting movement of a work piece, for example, a wood heel blank, with an edge thereof in engagement with said gage, in a predetermined path over said face of the support in traversing relation to said edges of the cutter to cause a surface of the work piece, for example an upper end of the heel blank, to be concaved. In accordance with a feature of the present invention, the illustrative machine is provided with mechanism which is operated in timed relation to the work piece moving means, for effecting relative translatory movement of the cutter and the support at approximately right angles to said face of the support whereby to vary the amount of projection of the locus of the cutting edges of the cutter beyond said face, and is also provided with mechanism, which is responsive to said relative translatory movement of the cutter and the support, for maintaining a constant distance between the gage and an intersection of the plane of the support and the locus of the cutting edges of the cutter irrespective of the amount that said locus projects beyond said face.

The support has the form of a horizontal table which is mounted for vertical movement with relation to the cutter and through a slot in which the cutter extends in projecting relation above a horizontal planar work supporting face of the table. The cutting edges of the cutter lie in a toroidal surface constituting the locus of said edges, centers of transverse curvature of said toroidal surface being arranged in a circle which constitutes the locus of said centers.

The gage in a preferred embodiment of the invention is fixedly positioned on the table and extends over one end portion of the slot with a planar face thereof arranged opposite the cutter. The heel blank to be concaved is automatically positioned and clamped in a jack which is moved, by mechanism similar to that disclosed in said Patent No. 2,038,636, in a closed path with the rim of the upper end of the blank in engagement with said planar face of the gage, thereby causing the upper end of the blank to traverse the cutter with the result that said upper end is concaved to form the wood heel.

In order that the wood heel shall have an attaching face which is of tapering depth rearward from its breast, it is desirable that the cutter project different distances above the planar face of the table during different portions of the heel blank concaving operation, and accordingly the table, as above explained, is raised and lowered by servo mechanism during the operation, the amount

of vertical movement imparted to the table by said servo mechanism during different portions of the concaving operation being controlled by a cam which is power driven in timed relation to the jack and a contour or effective shape of which may be varied in accordance with the desired shape and depth of the attaching face of the heel to be formed from the blank. It will be apparent that when the table is raised and lowered with relation to the cutter to vary the depth of the cut in the upper end of the wood heel blank, the distance between the planar face of the gage, which is fixed to the table, and an adjacent portion of the locus of the cutting edges of the cutter intersecting the plane of the face of the table will vary unless there is some provision for maintaining this distance constant. Accordingly, unless the abovementioned provision is present a flat land included between the concavity formed in the upper end of the heel and the rim or edge of said upper end will not be uniformly wide. Such a defect would render the heel unsalable.

With the above considerations in view the illustrative machine, in accordance with another feature of the present invention, is provided with servo mechanism operative in response to vertical movement of the table for swinging the cutter about an axis which is arranged substantially in the plane of the face of the table and lies in a plane of and is tangent to the circular locus of the centers of transverse curvature of the cutting edges of the cutter, the construction and arrangement being such that the spread of the locus of the cutting edges of the cutter above the table is constant and an adjacent end of said locus where it intersects the plane of the table is positioned a constant distance from the planar face of the gage irrespective of the heightwise position of the table and accordingly the amount of projection of the locus of the cutting edges of the cutter above said table.

By the use of the illustrative machine heels having attaching faces which are provided with marginal lands of uniform width and have concavities decreasing in depth rearwardly from their breast edges, may be quickly and effectively formed. The depth of the concavities formed in the attaching faces of the heels and the lengthwise slope of said concavities with relation to planes of the lands of said attaching faces may be readily varied in accordance with the thicknesses and shapes of the heel seat tabs formed upon the outsoles to be accommodated.

Fig. 1 is a front view of an illustrative machine for concaving the upper ends or faces of wood heel blanks to form wood heels;

Fig. 2 is a side elevation, partly broken away and on a larger scale than Fig. 1, of the machine;

Fig. 3 is a view of the machine on the line III—III of Fig. 2;

Fig. 4 is a view on the line IV—IV of Fig. 1 showing a heel blank receiving jack of the machine and also showing mechanism for opening and closing the jack and for feeding a heel blank into said jack;

Fig. 14 is a plan view showing the path of movement of the heel blank over the table and past the cutter during the concaving of the upper end or face of the heel blank;

Fig. 15 is a section on the line XV—XV of Fig. 6 showing portions of mechanism for operatively connecting the jack actuating mechanism to the cam slide;

Fig. 16 is a section on the line XVI—XVI of Fig. 3 showing portions of controlling mechanism of a servo unit for effecting swinging movement of the cutter.

Fig. 17 is an illustrative view on the line XVII—XVII of Fig. 16;

Figs. 18 and 19 show respectively in front elevation the relation of the table, and edge gage, the cutter and the heel blank during two different portions of the heel concaving operation;

Figs. 18a and 19a are plan views on the lines XVIIIa—XVIIIa and XIXa—XIXa respectively of Figs. 18 and 19, 25 the heel shown in Figs. 18 and 19 having been removed;

Fig. 20 is a section on the line XX—XX of Fig. 16 showing portions of the controlling mechanism for the servo unit through which the swinging movement of the concaving cutter is effected;

Fig. 21 is a section on the line XXI—XXI of Fig. 20;

Fig. 22 is a section on the line XXII—XXII of Fig. 3 showing a mounting for an air motor which operates the cutter;

Fig. 23 is a section on the line XXIII—XXIII of Fig. 35 22;

Figs. 24 and 25 are sections corresponding to portions of the section shown in Fig. 16 and illustrating a modified table and edge gage for use in the concaving of heel blanks to the form shown in Fig. 33;

Fig. 26 is a view on the line XXVI—XXVI of Fig. 24;

Fig. 27 shows in perspective a wood heel blank the upper end or face of which has been concaved by the first step of a concaving operation performed by the use of the above machine;

Fig. 28 shows in perspective the partially concaved wood heel blank of Fig. 27 after a second step of the concaving operation has been effected;

Fig. 29 shows in perspective a wood heel after the concaving of the wood heel blank has been completed;

Fig. 30 shows the heel illustrated in Fig. 29 partially in side elevation and partially in median longitudinal section;

Figs. 31, 32 and 33 are views similar to Figs. 27, 28 and 29 respectively showing a wood heel blank which has been concaved by the use of the machine provided with the modified table and edge gage illustrated in Figs. 24, 25 and 26, and

Fig. 34 shows a rear end portion of an inverted shoe to which the heel shown in Figs. 29 and 30 has been attached, portions of said heel and heel seat of the outsole of the shoe having been broken away.

The illustrative machine is described with reference to removing material from the flat upper end or face 40 (Figs. 18, 19, 27 and 28) of a Louis wood heel blank 42,

65 which has already been "turned" and "grooved," to form a Louis wood heel 44 (Figs. 29, 30 and 34) having an attaching face or cup 46. The illustrative machine, slightly modified, is also described with reference to removing material from the flat upper end or face 40a (Figs. 31 and 32) of a Louis wood heel blank 42a which has been "turned" and "grooved" to form a Louis wood heel 44a (Fig. 33) having an attaching face or cup 46a which is of slightly different shape from the heel attaching face or 75 cup 46. The operation, during which the heel attaching

faces 46, 46^a are formed, is commonly referred to as the "concaving" of the wood heel blanks 42, 42^a.

Wood heel blanks 42, 42^a are commonly concaved by the use of the machine disclosed in the above-mentioned Patent 2,038,636, said machine forming on the wood heel blanks an attaching face a longitudinal portion of which is of substantially uniform depth for about three-quarters of its length from its breast edge. As above explained, the heel 44, after having a cover 48 (Fig. 34) applied to it, is attached to a shoe 50 with a covered rim of its attaching face 46 firmly pressed into an overlasted counter portion 52 of an upper of the shoe, a "fitted" heel seat tab 54 of an outsole 56 of the shoe being included in the attaching face 46 of the heel 44 and upper breast corners of the heel being in engagement with heel breast receiving shoulders 58 formed upon the outsole.

Since the outsoles 56 of shoes 50 are of different thicknesses and the heel seat tabs 54 formed on said outsoles in the various factories are of different shapes, there has been considerable call for heels having attaching faces which will include heel seat tabs 54 of different shapes and sizes and will adequately support the heel end of the shoe upper against sagging and which will also allow the rim of the attaching face of the heel to be forced slightly into the overlasted counter portion of the shoe so that said counter portion shall merge attractively with the side and rear faces of the heel of the shoe.

It will be understood that except for slight differences in the shape of its attaching face 46^a, as hereinafter explained, the heel 44^a is identical with the heel 44 and the above statements relating to the heel 44 and its relation to the shoe also apply to the heel 44^a. The side and rear faces of the wood heel blanks 42, 42^a and the wood heels 44, 44^a will be collectively referred to as the "outer faces" of the wood heel blanks and the heels.

The illustrative machine comprises a vertically movable multipart table 60 having a planar or flat upper face 62 which is horizontal and receives the wood heel blank 42, upper end 40 down upon said face 62, a rotary or circular cutter 64 which has cutting edges 65 and extends through a slot 66 formed in the table and which projects above or beyond said face, and a gage 68 which is positioned on the table in overlapping relation to the slot and adjacent to the cutter. The present machine, as in the case of the machine disclosed in said Patent No. 2,038,636, is provided with a jack or carrier 70 (Figs. 1, 2, 4 and 5) in which the heel blank 42, supported on the face 62 of the table 60, is automatically positioned and secured, and by the use of which said blank is moved over said face of the table with a rim 47 (Figs. 5, 27 and 28) on the flat upper end 40 of the heel in forced sliding engagement with a flat surface 72 of the gage 68, in a predetermined path 74 (Figs. 4 and 14) past the cutter 64, to form the attaching face 46 of the heel 44. The jack 70, as herein-after explained, is bodily yieldable away from the flat face 72 of the gage 68 to insure the proper sliding engagement between the heel carried by the jack and the gage 68. The heel blank 42 is automatically fed to the jack 70 by a loader 76 (Figs. 1, 2 and 4) operated in timed relation with the jack. The operator places the heel blank 42 in the loader 76 while the prior heel blank is being concaved, said blank in the loader being fed automatically to the jack after an ejector finger 78 (Figs. 4 and 5) of the jack has removed the concaved heel 44 from the machine.

In order to provide the heel 44 with the attaching face 46 which, as best shown in Fig. 30, is of decreasing depth rearward from its breast or forward end, the table 60, during the first and last portions of the heel blank concaving operation, is raised and lowered respectively at right angles to its face 62 with relation to the rotary cutter 64 by herein-after described mechanism comprising a motor 80 (Figs. 1, 2, 3 and 11) of a servo unit 81 responsive to follower mechanism 82 operated by a multi-part cam 84 (Figs. 1, 8 and 9) mounted upon a slide 86 movable in timed relation with the jack 70. It is desira-

ble, for reasons which will be explained later, that the width of ribs or lands 88 (Fig. 29), 88^a (Fig. 33), which are formed at the rims of the peripheral portions of the attaching faces 46, 46^a of the heels 44, 44^a and are pressed into overlasted counter portions 52 of the shoes 50 shall be uniform.

It will be apparent that if the cutter 64 should remain in a constant operating position during the concaving operation while the table 60 is raised and lowered with relation to the cutter, a distance 90 (Figs. 18, 19, 18a and 19a) between the planar surface 72 of the gage 68 and an adjacent point of intersection 92 of a plane of the face 62 of the table and an arc 94, which lies in a locus 91 (Figs. 17, 18a and 19a) of the cutting edges 65 of the cutter and passes through an infinite number of points spaced greatest distances vertically from the face of the table, would vary and accordingly the land 88 formed on the heel 44 would not be of uniform width. A remote point of intersection of the plane of the face 62 of the table 60 and the arc 94 is indicated by reference numeral 92^a. With the above considerations in view the cutter 64, as will be explained in detail later, is swung in timed relation to the rise and fall of the table 60 about a fixed horizontal axis 98 (Figs. 1, 2, 3, 17 and 19a) which is included in a general plane 99 of rotation of the cutter 64 and which is parallel and arranged in close proximity to the face 62 of the table, the construction and arrangement being such that throughout the concaving operation the distance 90 remains constant irrespective of the heightwise position of the table. The arc 94 represents the line along which the cutter penetrates deepest into the work and may be referred to as a line of maximum cutting depth of the cutter.

The cutting edges 65 of the cutter 64 lie in the locus 91 which is of toroidal shape and may be referred to as a toroidal surface. Radial planes 93 (Fig. 18a) through the cutter 64 intersect the locus 91 along circular lines 95 (only one shown), each having a center of curvature 97 which, during rotation of the cutter, generates a circle or circular locus 101 (Figs. 18 and 19a). Each of the cutting edges 65 of the cutter 64 lies in a plane which is skewed with relation to the general plane 99 of rotation of the cutter and has substantially the form of an ellipse a center of which lies in the locus 101. Centers of curvature 97 of the circular lines 95 which lie in the toroidal surface 91 may be described as the centers of transverse curvature of the toroidal surface or the locus of rotation 91 of the cutting edges 65.

The cutter 64, as will be herein-after explained, is initially positioned in the machine so that the plane of the locus or circle 101 includes and is tangent to the axis 98 which is parallel to the face 62 of the table 60. Accordingly, the axis 98 may be described as lying in the plane of the locus or circle 101 and as being tangent to said locus or circle and substantially parallel to the face 62 of the table 60. When, during the concaving of the wood heel blank 42, the table 60 is raised and lowered relatively to the cutter 64, the face 62 of the table is raised or lowered with relation to the axis 98, said face remaining parallel to itself and at all times being located in the general vicinity of or in close proximity to said axis.

It will be noted (Fig. 18a) that when the rotary cutter 64 is so arranged that its general plane of rotation 99 forms a right angle with the face 62 of the table 60, the arc 94 of maximum cutting depth lies in a great circle 105 of the locus 91. When the heel blank 42 or 42^a is first presented to the cutter 64 the general plane of rotation 99 of the cutter is usually disposed at approximately a right angle to the face 62 of the table 60. During the concaving operation the cutter 64 may be swung to an extreme position in which its general plane of rotation 99 and accordingly the great circle 105 of the locus 91, which great circle is coincident with said plane of rotation, are disposed at an angle of about 30 degrees to the face 62 of the table 60. It will be noted that when the general plane

of rotation 99 of the cutter 64 is disposed at an acute angle to the face 62 of the table (Fig. 19a) the arc 94 is not included in a plane as it is in Fig. 18a, the center of said arc in Fig. 19 being located farther away from the great circle 105 than are the end portions of the arc which intersect the plane of the face 62 of the table 60.

It will be noted that the points of intersection 92, 92^a of the arc 94 with the plane of the face 62 of the table 60 shift slightly forward and rearward of the table along lines 107, 107^a respectively, which are parallel to the surface 72 of the gage 68, as the cutter is swung about the axis 98 and accordingly it is desirable that said surface 72 shall be of substantial length so as to be arranged opposite and equidistant from said points of intersection. It is with the above considerations in view that the work engaging face 72 of the gage 68 is flat instead of being convex as are the work engaging faces of the prior concaving machines of the general type herein disclosed.

Pivoted upon a bearing 100 (Figs. 2 and 3) secured to a main frame 104 of the machine is a horizontal suspension arm 106 which is integral with and may be described as carrying a gear box 108 for housing jack supporting and feeding apparatus 110 (Figs. 1, 6, 7 and 15) and which is movable about an axis 112 of said bearing. The suspension arm 106 is constantly urged clockwise as viewed from above and when the machine is idle is held in engagement with a stop screw 114 (Figs. 1, 2 and 7a), which is threaded into the main frame 104, by the following mechanism. Pivoted upon a shoulder screw 116 secured to the gear box 108 is a link 118 operatively connected to one arm of a bell crank lever 120 fulcrumed on a shoulder screw 121 secured to the main frame 104. Pivoted to the other arm of the bell crank lever 120 is a link 122 having a slot 123 through which projects a pin 124 mounted on a weight carrier 125 journaled upon a bearing pin 126 secured to the main frame 104. Mounted upon the weight carrier 125 is a heavy weight 127 having formed integral with it an arm 128 provided with notches 129 any one of which is adapted to receive the bearing pin 126, the weight being so positioned on the carrier 125 that the pin 124 is constantly urged counterclockwise as viewed in Fig. 2 in order constantly to urge, by the above described mechanism, the gear box 108 toward the stop screw 114. The force with which the gear box 108 is forced against the stop screw 114 may be varied by moving the weight 127 into different active positions upon the carrier 125. When the machine is in the process of concaving the wood heel blank 42 or 42^a the suspension arm 106 is not in contact with the stop screw 114 but has been forced away from said screw by reason of pressure exerted against the planar face 72 of the edge gage 78 by the rim 47 of the upper end 40 of the blank 42 or by a rim 47^a (Fig. 32) of the upper end 40^a of the blank 42^a which blanks are clamped respectively in the jack 70 and are guided in the path 74.

Freely slidable and rotatable in the gear box 108 of the suspension arm 106 is an ovoid-shaped gear 130 (Figs. 1, 6 and 7) a portion of which has an outline generally similar to that of the rims 47, 47^a of the wood heel blanks 42, 42^a respectively. The gear 108 has an upstanding flange 131 provided with a smooth outer face 132 which at all times is held in forced engagement with two rolls 134, 136, the roll 134 being secured to a vertical shaft 138 rotatably mounted in the gear box 108 and the roll 136 being rotatable on a bearing shaft 140 secured to said gear box. The shaft 138, which has secured to it a pinion 142 meshing with the ovoid-shaped gear 130, is driven by a pulley 144 (Figs. 1 and 2). Power for driving the pulley 144 is supplied by a belt 146 from a pulley 148 secured to the upper end of a drive shaft 150 rotatably mounted in the bearing 100. Secured to the lower end of the shaft 150 is a bevel gear 152 which is driven by a bevel gear 154 operatively connected to a shaft 156 of an electric motor 158. As will

be explained later, when the motor 158 is powered the machine operates automatically through continuous cycles, the wood heel blanks 42 or 42^a being placed by hand successively in the heel loader 76. In order to stop the machine the operator shuts off the motor 158 by the use of a switch 160, the machine then coming to rest at any portion of its cycle.

The ovoid-shaped gear 130 has a smooth inner face 162 (Figs. 6 and 7) against which pressure is exerted by 10 a roll 164 rotatably mounted on the lower end of a shaft 166 which is carried by one arm of a bell crank lever 168 fulcrumed on a bearing pin 170 secured to the gear box 108 and which projects through a large hole 172 in the top of the gear box. The lever 168 is constantly urged 15 clockwise, as viewed from above, by a strong spring 174 opposite ends of which are attached respectively to the lever and to a bolt 176 threaded into a lug of the gear box 108. It will thus be apparent that the roll 164 is at all times forced against the upstanding flange 131 of the 20 ovoid-shaped gear 130 causing it to engage the rolls 134, 136 while the pinion 142 rotates the gear.

The ovoid-shaped gear 130 has a depending tube portion to which is secured by screws 177 (Figs. 6, 7 and 15) a pinion 178 which, as will be hereinafter explained, 25 is operatively connected to mechanism adapted to cooperate with mechanism best shown in Figs. 11 and 12 for operating the cam carrying slide 86. Carried by and 30 slidingly mounted in the depending tube portion of the gear 130 is a coupling 180 having formed in it an elongated slot 182 (Fig. 7) through which passes a pin 184 secured to said tube portion. When the machine is idle the upper end of the slot 182 formed in the coupling 180 engages the pin 184, said coupling being constantly 35 depressed by a spring 186 upper and lower ends of which engage respectively a nut 188, which is threaded into the gear 130, and the upper end of the coupling. The coupling 180 and the depending portion of the gear 130 may be referred to as telescoping parts of a drive, one of said parts being constantly urged toward the table 60 by the 40 spring 186. The coupling 180 has formed at its lower end a dovetail rib 190 shaped and arranged to be received in a dovetail slot 192 (Fig. 5) formed in an upper slide 194 having in its lower surface a dovetail guide 45 shaped and arranged to be received in a dovetail slot 196 in a lower slide 198 which carries the jack 70. In order that the jack 70 may be initially moved into different adjusted positions with relation to the depending portion of the ovoid-shaped gear 130, the upper slide 194 is adjustable on the coupling 180 after releasing a 50 set screw 200 which is threaded into the upper slide and normally bears against said depending portion, and the lower slide 198 is adjustable on the upper slide by the use of an adjusting screw 202 which is rotatably mounted in the lower slide and is threaded into the upper slide.

The lower slide 198 has secured to it two depending pins 208 (Figs. 4 and 5) on which a guide 210 is mounted. The lower slide 198, the pins 208 and the guide 210 are rigidly secured together and may be considered as a holder for supporting and guiding the various moving parts of the jack 70. Rotatably mounted upon the pins 208 are finger levers 212, 212^a. The lever 212^a has threaded into it two adjustable fingers 214^a for engaging one side of the heel blank 42 or 42^a and the lever 212 has a finger 214 similar to the fingers 214^a and also has a finger 214^b which is adjustable in the lever 212 and is yieldable outward by spring action (not shown) away from the heel blank in the machine. The fingers 214, 214^a and 214^b point downwardly in predetermined directions and have inserted in recesses in their lower ends leather plugs for engaging the heel blank.

The levers 212, 212^a are constantly urged by a spring 216 (Fig. 4) to their open or heel blank receiving positions, said spring serving to force follower rolls 218, 218^a carried respectively by the levers 212, 212^a into engagement with a diverging cam portion 220 of a bar 222

slidable in a guideway 224 of the guide 210. The cam portion 220 of the bar 222 comprises faces 228, 230 which are arranged parallel to the guideway 224 and are connected by forwardly diverging faces 232. When the bar 222, actuated by mechanism hereinafter described, is in its forward position the rolls 218, 218^a are in engagement with the cam faces 230 of the bar 222, the fingers 214^a on the one hand and 214, 214^b on the other hand being in open positions in which the heel blank 42 or 42^a is fed into the jack 70 by the heel loader 76. When the bar 222 is in its rearwardmost position the rolls 218, 218^a are in engagement with the faces 228 of the bar 222 and the fingers 214, 214^a, 214^b are forced against the sides of the heel blank 42 or 42^a a breast of which is in engagement with back gage portions 234 of the guide 210 of the above-mentioned holder.

The bar 222 has shoulders 236, 238 which contact the guide 210 of the lower slide 198 to limit rearward and forward movements, respectively, of the bar and carries at its rear end a roll 240 adapted to fit in a notch 242 formed in one end of a lever 244 journaled on a bearing pin 246 secured to said lower slide. The lever 244 also has mounted on it rolls 248, 250 which, as will be hereinafter described, engage a fixed abutment 252 (Figs. 1 and 4) which is carried by a lever 256, to effect rearward and forward sliding movement, respectively, of the bar 222, that is, movement of the bar to the left and to the right as viewed in Fig. 4. Secured to the forward end of the bar 222 is the ejector 78 which is engaged by the breast of the heel blank 42 or 42^a moved into the jack 70 by the heel loader 76, said bar being moved rearward until the breast of the heel blank engages the back gage portions 234 between which the ejector slides. As will be hereinafter explained, after the concaving operation and as the finger levers 212, 212^a are opened, the ejector 78 moves rapidly forward into the space between the levers to force the heel blank, which has been concaved, from the machine. Since the jack operating abutment 252 and the mounting therefor are described in detail in said Patent 2,038,636 no further description of this mechanism is deemed to be necessary.

As the jack 70, which travels through continuous cycles when the machine is powered, moves to a heel blank receiving position opposite the loader 76, said loader moves the heel blank 42 or 42^a placed therein by the operator against the ejector 78 of the bar 222, the bar under pressure of the blank sliding rearward along the guideway 224 of the guide 210, thereby forcing the rolls 218, 218^a apart until the fingers carried by the levers 212, 212^a move into like contact with the heel blank 42 or 42^a the breast of which at this time is in close proximity to the back gage portions 234 of the guide 210. As the heel blank 42 or 42^a completes its movement to this position in the jack 70 the roll 248 strikes the abutment 252 thus forcing the bar 222 rearward slightly with the result that the cam faces 228 of the bar engage the follower rolls 218, 218^a causing the fingers 214^a on the one hand and the fingers 214, 214^b on the other hand to be forced against opposite sides respectively of the heel blank positioned in the jack and causing the breast of the heel blank to be pressed firmly against the back gage portions 234 of the guide 210. When the heel blank 42 or 42^a clamped in the jack has been moved over the upper face 62 of the table 60 and past the cutter 64 by a combined sliding and rotary movement with its rim 47 or 47^a in engagement with the planar surface 72 of the gage 68 through successive positions A, B, C and D (Fig. 14), the roll 250, which during rotation of the jack is in an outward position, engages the abutment 252 and accordingly moves the bar 222 forward along the guide 210 so that the cam surfaces 230 of the bar are opposite the rolls 218, 218^a thereby enabling the levers 212, 212^a and 212^b to be swung by the spring 216 to their open positions away from the heel blank and causing the ejector 78

of the bar to force the heel blank 42 or 42^a which has been operated upon, from the machine.

The heel loader 76 comprises a lever 258 (Figs. 1, 2 and 4) which is pivoted upon a bearing pin 260 carried by a slide 262 adjustably mounted in a guideway 259 of the table 60 and which is constantly urged by a torsion spring 264 to its rest or idle position shown in Fig. 4. In order to transfer the heel blank 42 or 42^a to the jack 70 the lever 258 is moved counterclockwise as viewed in Fig. 4 by the engagement of a roll 266 (Fig. 5), which is carried by an arm 268 secured to the lower slide 198, with a lever 270 (Figs. 1 and 4); the construction and arrangement being such that the lever 258 moves the heel blank 42 or 42^a into substantial engagement with the back gage portions 234 of the jack 70 as said jack moves slowly past its loading station and just before the bell crank lever 244, operating through mechanism above described, causes final clamping pressure to be applied to the heel blank. The lever 270 is rotatably mounted 20 on a pivot pin 272 carried by the slide 262 and is operatively connected yielding to the lever 258. The lever 258 carries an adjustable heel blank rest 274, which is engaged by the rear upper end of the heel blank upon the table 60, and a leaf spring holdown 276 for retaining the heel blank 42 or 42^a in engagement with said rest 274, said blank being slid over the table into the jack 70 by counterclockwise movement of the lever. Retractive or clockwise movement of the lever 258, as viewed in Fig. 4, is cushioned by a dash pot 278. Since the loader 76 and the mechanism for operating it are substantially identical with corresponding mechanism disclosed in detail in said Patent 2,038,636 no further description of this mechanism is believed to be necessary.

The rotary cutter 64 is mounted upon a shaft 280 rotatable about an axis 281 and projects upward through the slot 66 formed in the table 60, the edge gage 68 having its flat face 72 overlying an end portion of said slot and positioned adjacent to the cutter. In operating the machine the operator places the heel blank 42 or 42^a with its upper end 40 or 40^a in engagement with the face 62 of the table 60 in the heel loader 76 so that the rear end of the heel is in engagement with the rest 274 and its tread end is engaged by the leaf spring clamp 276. As the jack 70 moves slowly past its loading and unloading station in which a heel receiving opening, formed between the fingers 214^a on the one hand and the fingers 214 and 214^b on the other hand, is arranged opposite the heel loader 76, the roll 266 of the arm 268 strikes the lever 270 and operates said loader causing the heel blank 42 or 42^a placed in the loader, to be swung over the table to force the breast of said blank against the ejector finger 78, whereby to move the bar 222 rearward and then to move said breast substantially into engagement with the back gage portions 234 of the guide 210, the fingers 214, 214^a and 214^b, during such movement, swinging inward into engagement with the heel blank. Immediately after the heel blank 42 or 42^a has been thus positioned in the jack 70 the roll 248 of the arm 244 engages the abutment 252 with the result that the bar 222 is caused to move rearward in the guideway 224, the pairs of fingers carried by the levers 212, 212^a thereafter being moved inward with considerable pressure to clamp the positioned blank in the jack.

The lever 258 swings back to its rest position shown in Fig. 4 under the action of the torsion spring 254 as soon as the heel blank 42 or 42^a has been presented to the jack 70. As the heel blank 42 or 42^a clamped in the jack 70 is moved in the path 74 with its face 40 or 40^a in engagement with the face 62 of the table 60 past the cutter 64, the rim 47 or 47^a of the heel blank engages the flat face 72 of the gage 68 which cooperates with the table and the jack in the guiding of said blank past the cutter, the gear box 108 and accordingly the suspension arm 106, during such movement, being moved slightly about the axis 112 and away from the stop screw 114 by reason of pressure of the rim 47 or 47^a of the

11

heel blank 42 or 42^a against the gage as said blank partakes of the combined translatory and rotary movement of the jack. Movement over the table 60 of the heel blank 42 or 42^a, which is clamped to the jack 70, in the path 74 is continued until the roll 250 of the lever 244 strikes the abutment 252 causing the jack 70 to be opened as above described to permit the heel to be released and the ejector 78 to knock the heel 44, which has been formed from the blank 42, from the machine.

When during the operation of the machine the heel blank 42, which is clamped in the jack 70 and moves in the path 74 (Fig. 14), reaches position A the concaving cut shown in Fig. 27 is just starting, said cut progressing as the blank with its breast leading and its rim 47 in sliding engagement with the face 72 of the gage 68 traverses the cutter 64. When the heel blank 42 reaches position B the concaving cut shown in Fig. 27 has been completed and the heel is then rotated approximately 180° in a circular portion of the path 74 with its rim still in engagement with the face 72 of the gage 68 until the blank arrives at position C thereby additionally concaving the upper end 40 of the heel to the shape shown in Fig. 28. The heel blank 42, the rear end of which then faces rearward, thereafter moves rearward with its rim 47 continuing to slide along the surface 72 of the gage 68 until the blank reaches position D where the concaving cut is completed to form the heel 44. After the completion of the concaving operation the heel 44 formed from the blank 42 moves out of engagement with the edge gage 68 and the suspension arm 106 moves into engagement with the stop screw 114 the heel continuing to move, rear end leading, to a position E where it is ejected by mechanism above described, the jack thereafter advancing to its loading and unloading station opposite the loader 76 where it receives the next heel blank 42 to be concaved.

As above explained, it is desirable to form in the upper end 40 of the wood heel blank 42 an attaching face 46 which is of diminishing depth rearward from its breast. Accordingly, the table 60 of the illustrative machine, as above stated, is moved heightwise in timed relation to the jack 70 during the concaving operation by the use of mechanism which will now be described in detail.

The table 60 has a depending front apron 284 (Figs. 1, 2, 3, and 11) provided with a dovetail guideway 286 fitting slidably on a vertical dovetail guide 288 of the main frame 104. The table 60 is supported in a predetermined but variable horizontal position by a fluid-pressure operated piston 290 which is slidable in the motor 89 of the servo unit 81 and is pivotally connected to the lower end of the apron 284 of the table. In order to balance the weight of the table 60 and the mechanism supported by said table the depending apron 284 has attached to its lower end a strong spring 294 the upper end of which is attached to the main frame 104. Upper and lower chambers 296, 296a (Fig. 11) which are filled with oil and are formed by the piston 290 and the casing of the motor 80 are intermittently connected to sources of high and low pressure oil in accordance with the setting of a valve 298 of the servo unit 81. The operation of the valve 298, as will be hereinafter described, is controlled by the multipart cam 84 which is carried by and may be initially adjusted with relation to the slide 86, said slide being movable transversely along a guideway 300 (Figs. 1, 8 and 11) formed in the lower front portion of the main frame 104.

The slide 86 has secured to it by screws 302 a rack 304 meshing with a pinion 306 which is mounted on a shaft 308 journaled in a bearing 310 secured to a boss of the main frame 104 and which is supported by said bearing. Formed integral with the pinion 306 is a coupling ring 312 (Figs. 11 and 12) having three recesses 314 which, during a concaving portion of the cycle of the machine, are engaged by teeth 316 of a coupling sleeve 318 provided with elongated slots 320 adapted to receive a pin

12

322 extending through and secured to the shaft 308. Interposed between the pin 322 and a flanged portion of the coupling sleeve 318 is a spring 324 which constantly urges the coupling sleeve against the coupling ring 312. When the slide 86 engages a stop screw 326 (Figs. 1, 2, 3 and 11) threaded into the main frame 104 the recesses 314 of the coupling ring 312 are arranged respectively in receptive adjacency to the teeth 316 of the coupling sleeve 318 which is rotatable with the shaft 308. The shaft 308 is operatively connected by a flexible shaft 328 (Figs. 1, 2, 11 and 15) to a stub shaft 330 (Figs. 6 and 15) rotatable in the outer ends of arms 332, 334 which are journaled respectively upon the depending portion of the gear box 108 and a bearing pin 336 secured to the bottom of the gear box 108.

The cam slide 86 is moved to the right, as viewed from the front of the machine (Figs. 1 and 8), from a starting or retracted position in timed relation with the ovoid-shaped gear 130 by a mechanical drive including various members referred to above and hereinafter described in detail and is moved back to its retracted position from a projected position by hereinafter described fluid-pressure means. The shaft 308 is raised by a cam 338, which is secured to a screw 340 in a channel 348 of a rearwardly extending lug 342 secured by a screw 344 to the slide 86, as said slide reaches its projected position or limit of movement to the right as viewed from the front of the machine. The screw 344 passes through an elongated slot 346 in the slide and is threaded into the lug 342, which has a vertically disposed forward projection fitting in a vertical slot in the slide, the construction and arrangement being such that the lug 342 may be initially secured in different heightwise positions to the slide 86. The cam 338 has threaded into it the screw 340 which passes through an elongated slot in the lug 342, the construction and arrangement being such that the cam may be secured in different positions lengthwise of a channel 348 of the lug. Journaled on the shaft 308 just below the bearing 310 is a thrust bearing 349 a lower raceway of which is in engagement with a spring 354. Supported by a nut 350 threaded onto the lower end of the shaft 308 is a marginally beveled cam disk 352 which is forced against the nut by the spring 354.

When the slide is in its retracted or starting position at the left end of the guideway 300, as viewed from the front of the machine, the shaft 308 is in a lowered position, the teeth 316 of the coupling sleeve 318 then engaging in the recesses 314 of the coupling ring 312 of the pinion 306, the shaft, which is constantly urged downward by the spring 354, having been positively lowered to a predetermined position by reason of the disk 352 having been overridden by an eccentrically mounted depressor pin 356 adjustably mounted in a bearing bracket 358 which is secured by the use of screws 360 to the slide 86 and moves along a transverse horizontal slot 362 formed in the main frame 104. The bracket 358 extends through a slot 359, which is formed in the slide 86 and along which the bracket may be moved into different adjusted positions on the slide, and has threaded into it a screw 361 for securing the depressor pin 356 in its proper adjusted position in the bracket. In order to retain, during translatory movement of the slide 86 to the right and to the left respectively, the shaft 308 in a lowered driving position and a raised nondriving position, the shaft is provided with lower and upper circumferential channels 364, 364^a which may be moved selectively into alignment with spring-pressed plungers 366 carried by the bearing 310.

The depressor pin 356 may be secured to the slide 86 in different adjusted positions lengthwise of the guideways 300 by releasing the screws 360 and sliding the bracket 358 lengthwise along the slot 359 of the slide 86, the adjustment being such that when the slide returns to its retracted position shown in Figs. 1 and 8 the pin serves positively to depress the shaft 308, causing the teeth 316, 75 which are then in register with the recesses 314 in the

coupling 312 of the pinion 306, to be drawn into the recesses. As the slide 86 reaches its projected position or the right end of its stroke, as viewed in Figs. 1 and 8, the lower end of the shaft 308 is engaged by the cam 338 causing the shaft to be raised in the bearing 310 and the teeth 316 of the coupling sleeve 318 to be lifted out of the recesses 314 of the coupling ring 312.

As the shaft 308 is uncoupled from the pinion 306 a screw 367 (Figs. 1 and 8) adjustably secured to the slide 86 closes a normally open switch 369 (Figs. 1, 3 and 8a) causing a solenoid 373 to be energized with the result that a plunger 375 of a valve 377 is moved to its dotted line position shown in Fig. 8a to allow high pressure oil in a line 379 to be available for a line 370 leading to a chamber 371 (Figs. 1 and 3) formed by a cylinder 372 and a piston 374 which is pivotally connected to the slide, to move said slide to its retracted or starting position.

When the switch 369 is closed, a coil 381 of a relay is energized causing a normally open switch 383 to be closed and a holding circuit 385 to be established with the result, after the screw 367 has been moved away from the switch 369 allowing it to be opened under spring action, the solenoid 373 remains energized to retain the plunger 375 in its dotted line position. As the slide 86 reaches its starting position shown in Figs. 1 and 8 a screw 387 mounted on the slide 86 opens a normally closed switch 389, thus de-energizing the solenoid 373 with the result that the plunger 375 is moved to its full line position in which the high pressure line 379 is cut off from the line 370 then open to an exhaust line 391. When the exhaust line 391 is open to the line 370 the high pressure line 379 is open to a line 393 opening into a passage 440 of the valve 298, hereinafter referred to, to render the servo unit 81 active in response to movement of the slide 86. High pressure oil available for the passage 440 of the valve 298 operates the servo unit 81 in response to movement of the cam 84 to the right as viewed in Figs. 1 and 8. With the above construction it will be apparent that when the cam 84 is moved from its projected to its retracted position, high pressure oil is cut off from the servo unit 81 with the result that the table 60 during this time remains at rest. In order to insure that pressure supplied to the line 370 shall not be so great that it moves the slide 86 too quickly to its retracted position, a pressure regulating valve (not shown) may be inserted in said line.

The cam slide 86 has formed at its upper central portion an opening 376 (Figs. 1, 8 and 9) for receiving inclined tracks 378, 378a of the cam 84. The inclined tracks 378, 378a of the cam 84 have formed integral with them gear segments 380, 380a respectively slidably mounted in arcuate channels 382 in the rear face of the slide and meshing with pinions 384, 384a which are operatively connected to each other and are secured respectively to shafts 386, 386a journaled in the slide 86. The arcuate channels 382 and the gear segments 380, 380a are centered respectively about horizontal axes 388, 388a which are arranged at right angles to the path of movement of the slide and pass through the outer ends respectively of follower surfaces 390, 390a of the inclined tracks 378, 378a. In order initially to move, through the same angle which may be varied, the inclined tracks 378, 378a about the axes 388, 388a respectively into different adjusted positions in which the follower surfaces 390, 390a thereof are inclined to the horizontal and accordingly to the path of movement of the slide 86, the shaft 386 has secured to it a knurled knob 392. The inclined tracks 378, 378a are retained in the desired angular positions in the slide 86 by a draw screw 394 which fits in a bore of the slide and passes through an arcuate slot 396 in the gear segment 380a, said draw screw being effectively clamped to the slide by a knurled nut 398 threaded onto the screw.

Formed in the front central portion of the slide 86 is a vertical channel 400 which fits slidably a central

track 402 having an upper flat horizontal surface 404 opposite ends of which laterally overlap faces of the inclined tracks 378, 378a. The front surfaces of the slide 86 and the track 402 respectively may be calibrated as indicated at 405 in order to position the track initially in the channel 400. The angle at which the follower surfaces 390, 390a are disposed to the horizontal may also be readily determined by suitable calibrations (not shown). The central track 402 of the cam 84 may be secured in different heightwise positions along the channel 400 of the slide 86 by a screw 406 threaded into the slide, a shank portion of said screw passing through an elongated slot 407 formed in said central track and a head of said screw being clamped against the initially adjusted central track.

As will be explained later, during movement of the slide 86 along its guideway 300 a lower straight edge 409 of a follower or feeler 408 of the valve 298 of the servo unit 81 is engaged by flat upper surfaces 410, 410a of the inclined tracks 378, 378a and by the horizontal surface 404 of the central track 402, said cam, as above explained, acting through said servo unit to control the elevation of the table 60. Journaled on a bearing screw 412 (Figs. 1, 3 and 11) threaded into the main frame 104 is a lever 414 one end of which is operatively connected to a projection of the apron 284 of the table 60 and the other end of which is pivotally connected to an undercut portion 416 of a housing 418 of the valve 298, said undercut portion being mounted for vertical sliding movement in a guide 420 secured to the main frame. As above stated, the cam carrying slide 86 is moved from its retracted position to the right, as viewed from the front of the machine, along the guideway 300 in timed relation with the jack which moves, in the path 74, the heel blank 42 or 42a along the upper surface 62 of the table 60 with the rim 47 or 47a of said blank in engagement with the gage 68.

The cam follower 408 comprises a spool portion 422 (Figs. 8, 10 and 11) which is slidable in a vertical bore 424 of a bearing sleeve 425 secured to and forming part of the housing 418 of the valve 298. Formed in the housing 418 and in communication with the bore 424 are passages 428, 430 connected by lines 434, 432 to the chambers 296, 296a respectively of the motor 80. Also in communication with the bore 424 are passages 436, 438 which lead to a sump or exhaust (not shown), and the above-mentioned passage 440 which is open to the line 393 and, except when the slide 86 is moving toward its retracted position, is connected to a source of high pressure fluid. The passages 436, 438 are normally covered by cylindrical surfaces or lands 442, 444 of the spool 422 of the follower 408 and the passage 440 is normally covered by a cylindrical surface or land 446 of said spool portion, the follower then being in a "balanced" position in the housing 418 as shown in Fig. 10.

The follower 408 has formed integral with it a flange 447 bored to receive a threaded rod 448, which is secured to the housing 418, and mounted on the rod are nuts 450, 452, a spring 454 being interposed between the nut 450 and the flange. When the jack 70 moves the wood heel blank 42 from a position in which it is loaded into said jack to the position A in the path 74 where the cut shown in Fig. 27 begins, the cam slide 86 is moved to the right, as viewed in Figs. 1 and 8, the surface 410 of said slide running along the lower straight edge 409 of the follower 408 which remains in its balanced position since this surface is parallel to the guideway 300 and, accordingly, the servo unit 81 is not rendered active to impart vertical movement to the table 60. As the heel blank 42 in the jack 70 moves from position A to position B in the path 74 to effect the concaving cut shown in Fig. 27 the cam slide 86 progresses to the right, the follower 408 riding down the surface 390 of the inclined track 378 and, accordingly, being depressed relatively to the housing 418

15

from its balanced position in said housing, thus rendering high pressure fluid available for the lower chamber 296^a of the motor 80 and rendering the upper chamber 296 of said motor open to exhaust or sump pressure with the result that the table 60 is raised vertically at a predetermined speed along the dovetail guide 288 in accordance with the inclination of the surface 390 from the horizontal. As the table 60 rises, the housing 418 of the valve 298 "washes out" the displacement of the follower 408 and this cycle of operations continues until the follower reaches the place where the planes of the surfaces 390, 404 of the tracks 378, 402 respectively intersect, the depth of the cavity formed in the attaching face 46 of the heel blank during this stage of the operation diminishing as it extends rearward from the breast of the heel as shown in Fig. 30 by reason of the fact that the table 60, during this part of the operation, is raised relatively to the cutter 64.

As the heel blank 42 in the jack 70 moves from its position B to its position C in the path 74 the slide 86 continues to move to the right in timed relation with the jack 70, the follower 408 being engaged by the surface 404 of the central track 402 and since such surface is parallel to the guideway 300 it will be apparent that the spool portion 422 of the follower 408 remains in its balanced position in the housing 418 and accordingly the table 60 remains stationary, the heel blank 42, during this time being rotated by the jack over the face 62 of the table with its rim 47 in engagement with the gage 68 and the concaving cut progressing from its stage shown in Fig. 27 to its stage shown in Fig. 28. As the heel blank 42 in the jack 70 moves from a position C to a position D in the path 74, the cam slide 86 continues to move to the right (Figs. 1 and 8) and during this movement the cam follower 408 is engaged by the surface 390^a of the inclined track 378^a, the spool portion 422 of the follower being continuously raised with relation to the housing 418 with the result that high pressure fluid of the servo unit 81 is made available for the upper chamber 296 of the cylinder 292 and the lower chamber 296^a is open to oil under exhaust or sump pressure, thus causing the table 60, by the action of the servo unit 81, to be lowered to the vicinity of its starting position, the concaving of the attaching face 46 of the heel blank 42 progressing from its stage shown in Fig. 28 to its completed stage shown in Fig. 29 to form the wood heel 44. At the time that the concaving of the wood heel blank 42 has been completed the follower 408 is still engaged by the cam surface 390^a but is in the vicinity of the upper surface 410^a of the slide 86 and as soon as said follower reaches the surface 410^a downward movement of the table ceases. It will be noted that soon after the follower 408 has been in engagement with the surface 410^a the lower end of the shaft 308 is engaged by the cam 338 carried by the slide 86 thereby causing the teeth 316 of the sleeve 318 to be disengaged from the recesses 314 in the coupling ring 312 with the result that the driving connection between the jack 70 and the slide is temporarily disengaged and movement of the slide to the right, as viewed from the front of the machine, ceases.

As the slide 86 reaches the end of its movement to the right the screw 367, carried by the slide, closes the switch 369 thus causing, through the provision of fluid pressure operated means above described, the piston 374 to move the slide back to its starting position against the stop screw 326. A dash pot (not shown) may be provided for retarding movement of the slide as it arrives at a position adjacent to the stop 326.

As above explained, it is desirable that the land 88 of the attaching face 46 of the heel blank 42 shall be of uniform width. It will be apparent that should the axis of rotation 281 of the cutter shaft 280 remain fixed during the concaving operation, while the table is raised and lowered as above described, the width of the land 88 formed on the blank will not be uniform and the heel

16

will not be marketable. Accordingly, during the concaving operation and as previously stated the rotary cutter 64 is swung about the axis 98 which lies approximately in the surface 62 of the table and which is approximately tangent to and lies approximately in the plane of the circle or locus 101 of the centers of transverse curvature 97 of the toroidal surface 91.

The cutter 64 and operating mechanism therefor are supported upon a yoke or carrier 476 having a pair of trunnions 478 (Figs. 1, 2, 3 and 24) which are journaled in aligned bores 480 of pedestals 482 screwed to and forming part of the main frame 104. Mounted upon the yoke 476 by means hereinafter described is an air motor 484 having a shaft 486 to which is keyed a pulley 488 operatively connected by belts 490 to a pulley 492 fixed to the cutter shaft 280 which is journaled in a U-shaped bearing block 494. The rotary cutter 64 is secured to the shaft 280 by a nut 496. The bearing block 494, which may be described as forming part of the yoke or carrier 476, is provided with a dovetail guideway 498 fitting slidably on a dovetail guide, the block having rotatably mounted on it an adjusting screw 500 threaded into the main portion of the yoke. The cutter 64, by the use of washers (not shown), may be initially positioned lengthwise of its axis 281 so that its general plane 99 of rotation includes the fixed axis 98 which constitutes a common axis about which the trunnions 478 are centered. The adjusting screw 500 is provided for the purpose of raising or lowering the bearing block 494 so as initially to move the locus 101 into tangential relation with the fixed axis 98, such adjustment being effected during the initial setting up of the machine or after the cutter 64 has been changed and/or sharpened. The yoke 476 together with its block 494 and the cutter 64 may be swung about the axis 98 between short and long dash-line positions shown in Fig. 2 in timed relation with the vertical movement of the table 60, the construction and arrangement being such that, irrespective of the angular position of the cutter, the arc 94 of maximum cutting depth of the cutter shall intersect the plane of the table along the line 107 which is parallel to the planar face 72 of the edge gage 68. Since the axis 98 is parallel to the face 62 of the table 60 and lies in the plane of and is substantially tangent to the locus 101, it will be apparent that a central point of the arc 94 will not move heightwise as the cutter is swung into different operating positions.

During the concaving of the heel blank 42 to form in successive steps (shown in Figs. 27, 28 and 29) the attaching face 46 of the heel, the edge gage 68 and a testing plate or feeler 520 (Figs. 1, 3, 16 and 21), hereinafter described, are rigidly secured to the table 60. The attaching face 46 of the heel 44 has a longitudinal central ridge 521 (Fig. 29) which commonly increases in width and prominence as it approaches a high area 518, the shape of said ridge being dependent to a considerable extent upon the relative width of the upper end 40 of the heel blank 42 at its forward end and in the vicinity of said high area. The presence of the ridge 521, which is of negligible prominence, is of no practical disadvantage but in order to improve the appearance of the attaching face 46 of the heel 44 it is proposed to provide the heel 44^a having the attaching face 46^a which is formed in three stages shown in Figs. 31, 32 and 33 and includes a central ridge 523 which is less prominent than the ridge 521 on the attaching face 46 of the heel 44. In order to form the attaching face 46^a the illustrative machine is provided with a table 60^a (Figs. 24 and 25), which corresponds to the table 60, and is also provided with an edge gage 68^a and a feeler 520^a which, as will be hereinafter explained, move vertically with the table as well as transversely (that is lengthwise of the axis 98) with relation to said table, the construction and arrangement being such that during the time that the heel blank 42 moves between positions A and B and between posi-

tions C and D the center of the arm 94 of maximum cutting depth will approach as nearly as permissible (depending upon the contour of the heel) the longitudinal heightwise median plane of the heel with the result that the ridge 523 formed upon the attaching face 46^a of the heel 44^a will be less noticeable than the ridge 521 formed upon the attaching face 46 of the heel 44.

The table 60 comprises a platform 522 (Figs. 1, 2, 3 and 16) rabbeted to receive wear plates 524, 526 which are approximately identical and are secured by screws 528, 530 respectively to the platform. The wear plate 524, over which the wood heel block 42 or 42^a is slid in the path 74 as above explained, has formed in it the slot 66, inner margins of the plate which form the slot being undercut as best shown in Fig. 16. The wear plate 526 has a slot 532 which is substantially the same size and shape as the slot 66, and extending through the slot and above and beyond the surface 62 of the table 60 is a pattern 534 which has a toroidal surface 536 identical with the upper half of the toroidal locus 91 of the cutting edges 65 of the cutter 64 and which has a great circle thereof arranged in alignment with and in a parallel relation to the great circle 105 of the locus 91.

Movable transversely or lengthwise of the axis 98 into different fixed operating positions along the bottom of the platform 522 of the table 60 is a slide 540 which is spaced from the edge gage 68 by a block 542, the edge gage 68, the block and the slide being secured together by a pair of dowels 544 and a screw 546 and the block engaging opposite sides of an elongated guide slot 548 formed in the platform. The slide 540 has at its right end, as viewed in Fig. 16, a depending lip in which is rotatably mounted an adjusting screw 550 threaded into a depending flange which forms part of the platform 522 and engages opposite sides of a guide slot 552 in the slide. Mounted upon the right margin of the upper surface of the platform 522 of the table 60, as viewed from the front of the machine, is a coupling plate 554 having formed in its upper surface a U-shaped slot 556 in which fits a flange of the feeler 520. The feeler 520 cooperates with the pattern 534 to operate a servo unit 558 which controls mechanism for swinging the cutter about the axis 98 in response to the rise and fall of the table, as will be hereinafter explained.

The coupling plate 554 may be secured in different adjusted positions to the platform 522 by a screw 560 which is threaded into the platform 522 and the shank of which engages opposite sides of a slot 562 in the plate, and also by a screw 564 which is threaded into the platform and the shank of which engages opposite sides of opposite slots 566, 568 formed respectively in the plate 554 and in the flange of the feeler 520. The coupling plate 554 has threaded into it a shoulder screw 570 which fits in a circular bore of the slide 540 and engages opposite sides of an elongated slot 572 formed in the platform 522 and serves to secure the coupling plate to the slide. The engagement of the block 542, which is secured to the slide 540, in the slot 548 of the platform 522, the engagement of the shoulder screw 570, which is carried by the slide, in the slot 572 of the platform and the engagement of the depending flange of the platform in the slot 552 of the slide insures that, when the adjusting screw 550 is rotated, the slide 540 and the gage 68 will move as a unit in a rectilinear path extending transversely of the table and lengthwise of the axis 68. The engagement of the shoulder 570, which is carried by the slide 540, in the slot 572 of the platform 522, the engagement of the screw 560 in the slot 562 of the coupling plate 554 and the engagement of the screw 564 in the slot 566 of the coupling plate insures that the coupling plate shall be moved transversely of the table 60 and lengthwise of the axis 98 together with the slide 540 (assuming that the screws 560, 564 are released) in response to rotation of the adjusting screw 550.

In order initially to set the edge gage 68 in its desired

active position lengthwise in the slot 548 in accordance with the width of the land 88 to be formed on the attaching face 46 of the heel 44, the operator, after releasing the screws 560 and 564, turns the adjusting screw 550 causing the slide 540 and accordingly the edge gage 68 and the coupling plate 554 to move lengthwise of the axis 98. After the edge gage 68 has been properly adjusted in the platform 522 the operator tightens the screw 560 in order rigidly to secure the coupling plate 554 to the platform and slides the feeler lengthwise in the slot 556 of the coupling plate 554 until an edge 574 of the feeler engages the toroidal face 536 of the pattern 534, the screw 564 then being tightened in order rigidly to secure the feeler to the platform 522.

Secured by screws 576 (Figs. 1, 3 and 16) to the yoke 476 is a bracket 578 upon which are supported the pattern 534 and a control valve 580 of the servo unit 558 which, by mechanism hereinafter described, swings the yoke about the axis 98 in response to the rise and fall of the table 60. In order to insure that the bracket 578 shall be held rigidly to the yoke, after the bearing block 494 has been initially adjusted on the yoke, the yoke has an upstanding clamp portion 582 which is adapted to receive a flange of the bracket, a screw 584 being provided to secure the clamp portion to said flange.

To insure that the belts 490 for driving the cutter may be tightened after the block 494 has been adjusted in the yoke 476 there is mounted in a circular recess of the yoke an eccentric ring 586 (Figs. 3, 22 and 23) having a circular recess 588 for receiving a sleeve 590 to which the air motor 484 is secured by screws 592. The sleeve 590 is threaded for receiving a clamp collar 594 which after the air motor 484 has been properly adjusted on the yoke 476 may be clamped against the yoke to secure the sleeve to said yoke.

The bracket 578 of the yoke 476 is cut away to provide a ledge 596 (Figs. 16, 21 and 25) upon which the pattern 534 is slidable through a distance of about 20 thousandths of an inch in opposite directions 598, movement of the pattern in said opposite directions being limited by the engagement of the pattern with shoulder screws 600 which are threaded into the bracket 578 of the yoke 476 and have heads overlying the forward face of the pattern. Secured to the bottom of the pattern 534 is a pin 602 which passes through an elongated slot 604 formed in the bracket 578 and engages in a circular slot 606 formed in a rod 610 slidable in a bore 612 of the bracket, any substantial amount of rotation of the rod in the bore being insured against by the engagement of a guide pin 614, which is threaded into the bracket, in a channel 616 of the pin. The rod 610 has a shank onto which is threaded a nut 618 and interposed between the bracket 578 of the yoke 476 and the nut is a spring 620 for constantly urging the pattern 534 to the left, as viewed in Fig. 21.

Pivots connected to the rod 610 is a lever 622 journaled at 624 to the bracket 578 and pivotally connected to a rear end portion of said lever is a multipart plunger 626 of the valve 580. The valve 580 is substantially identical with the valve 298 and controls flow of high pressure oil to a pilot valve 628 (Fig. 3) which in turn controls flow of oil to faces 630, 632 respectively of a piston 634 (Figs. 1, 2, and 3) movable in a chamber of a cylinder 636 secured to the main frame 104. When the yoke 476 is in its starting position shown in Figs. 1 and 3 in which the general plane 99 of rotation of the cutter 64 is disposed at substantially right angles to the face 62 of the table 60, the piston 634 is in engagement with a rear wall of the cylinder 636. The cylinder 636 may be shifted slightly lengthwise into different active positions in the main frame 104 to vary the rest position of the piston 634 and, accordingly, the starting position of the cutter 64.

The forward end of the piston 634 is operatively connected through a link 638 to a crank arm 640 secured

to the right trunnion 478 (as viewed from the front of the machine). When the cam follower 408 is engaged by the horizontal upper surface 410^a of the slide 86, downward movement of the table 60 has moved the pattern 534 to its extreme right position shown in Fig. 21 upon the screws 600, the piston 634 having been displaced to its extreme rearward position and oil which is under pressure and operates against the face 632 of the piston being effective to retain the cutter in a substantially vertical starting position in accordance with the position of the cylinder 636 in the main frame 104. As the face 390 of the cam 84 slides along the cam follower 408 the table 60 is raised as above described and the pattern 534 acted upon by the spring 620 slides to the left as viewed from the front of the machine with the result that the servo unit 558 supplies oil to the face 630 of the piston 634 to swing the yoke 476 and, accordingly, the cutter 64 counterclockwise as viewed in Fig. 2 about the axis 98 a predetermined number of degrees in accordance with the amount of upward movement of the table 60, the heel blank 42 during this time being moved between positions A and B by the jack 70 to concave the upper end 40 of the heel blank 42 to the form shown in Fig. 27.

During the time that the cam follower 408 is engaged by the surface 404 of the cam 84 the table 60 remains stationary in its elevated position and the plunger 626 of the control valve 580 will remain in a closed or balanced position with the result that the yoke 476 also remains stationary in its maximum angle of swing for the particular heightwise movement of the table while the heel blank is being swung between the positions B and C whereby to advance the concaving cut from the stage shown in Fig. 27 to the stage shown in Fig. 28. As the cam surface 390^a slides along the cam follower 408, the heel blank 42 during this time being moved along the path 74 between positions C and D, the table is depressed causing the pattern 534 to be displaced to the right as viewed in Figs. 1 and 8 upon the shoulder screws 600, thereby rendering high pressure oil of the servo unit 558 available for the face 632 of the piston and thus swinging the cutter 64 and the pattern 534 back to their starting positions in which the axis 281 of rotation of the cutter is substantially parallel to the face 62 of the table, the concaving cut during this time progressing from its stage shown in Fig. 28 to its completion stage shown in Fig. 29. As the table 60 reaches its lowered or starting position the piston 634, as above explained, engages the rear end of the cylinder 636, thereby establishing the starting position of the cutter 64 and the pattern 534. It will be noted that as the table 60, the cutter 64 and the pattern 534 reach their starting positions, the pattern, which is engaged at one point by the feeler 520, has been displaced to the right, as viewed in Fig. 21, with the result that oil pressure is maintained against the face 632 of the piston to retain the table in its starting position. As the jack 70, after the concaving of the wood heel blank 42, continues to move in its path 74 preparatory to ejecting the blank from the machine the surface 410^a of the slide 86 moves along the feeler 408 which remains stationary with the result that the table 60 remains stationary. As soon as the cam 338 carried by the slide 86 engages the shaft 308 it raises the shaft out of driving relation with the pinion 306 which meshes with the rack 304 and substantially at the same time the screw 367 closes the switch 369 with the result that the piston 374, operated by mechanism as above described, moves the slide back to its starting position and at the same time the servo unit 81 is rendered inactive temporarily by cutting off high pressure oil from the passage 440. When the slide 86 has returned to its starting position shown in Figs. 1 and 8 the switch 389 is opened by the screw 387 carried by the slide with the result that the line 370 is open to exhaust to render the piston 374 inactive and the passage 440 is again opened to high pressure oil and the shaft 308 is lowered into

driving relation with the pinion 306 which meshes with the rack 304 of the slide 86.

In order to provide the heel 44^a which is essentially the heel 44 with its ridge 521 and high area 518 reduced, the edge gage 68^a which is similar to the edge gage 68 and which during the time that the forward lateral portions of the attaching face of the heel are being formed, is moved respectively slightly over a table 60^a away from and toward the cutter 64 with the result that there is slightly more overlapping of the concaving cuts than there is during corresponding cuts of the concaving operation as performed by the machine constructed as above described.

As the concaving cut progresses rearward from the forward end of the heel blank 42 the width of the cut is increased slightly to produce a marginal edge 644^a on the heel blank 42^a which corresponds to a marginal edge 644 formed on the heel blank 42. The increased overlapping of the cuts is effected by moving the edge gage 68^a away from the cutter while the concaving cut shown in Fig. 31 is being made and by moving the edge gage toward the cutter as the concaving cut finishes the trimming of the attaching face of the heel from its condition shown in Fig. 32. It will be apparent, since the edge gage 68^a is moved away from the cutter 64, that unless said cutter is swung about the axis 98 to compensate for the movement of the edge gage on the table 60 the land 88^a will not be uniformly wide. Accordingly when forming the face 46^a of the heel 44^a the cutter 64 is swung about the axis 98 suitable amounts to compensate for the transverse movement of the edge gage 68^a as well as to compensate for the heightwise movement of the table 60^a which as above stated is substantially identical with the table 60.

When the machine is equipped to form the attaching face 46^a of the heel 44^a the left pedestal 482, which constitutes part of the main frame 104, has formed integral with it an L-shaped holder 648 (Figs. 24 and 26) having a slot 652. Mounted upon the holder 648 is a block 654 having secured to it a stud 656 which passes through the slot 652, said block having formed in it a cam groove 658 and being held in different adjusted positions upon the holder by a nut 660. Secured by screws 662 to a slide 664 movable transversely along the bottom of a platform 522^a of the table 60^a and lengthwise of the axis 98 is an angle bar 668 which carries a cam roll 670 fitting in the cam groove 658 of the block 654.

The platform 522^a has formed in it a pair of rectilinear slots 672 which are in alignment and through which pass screws 674 respectively which fit in circular bores in the slide 664 and are threaded into the edge gage 642, said screws having mounted on them spacer sleeves 676 which engage respectively opposite sides of the slots 672 and assist in guiding the edge gage and the slide in a rectilinear path 677 extending lengthwise of the axis 98. The platform 522^a which is substantially like the platform 522 has rabbeted portions in which fit plates 524^a, 526^a corresponding to plates 524, 526 of the table 60 and having slots 66^a, 532^a which are identical with the slots 66, 532 and are adapted to receive respectively the cutter 64 and the pattern 534.

Mounted upon the platform 522^a, which includes the plates 524^a, 526^a, are a coupling plate 554^a and a feeler 520^a which are generally similar to the coupling plate 554 and the feeler 520. The coupling plate 554^a has threaded into it a shoulder screw 680 which fits in a circular bore of the slide 664 and engages opposite sides of an elongated slot 682 of the platform 522^a and which cooperates with the spacer sleeves 676 on the screws 674 in the guiding of the slide 664 and the edge gage 68 in said transverse rectilinear path extending lengthwise of the axis 98. Extending through and engaging opposite sides of a slot 684 formed in the coupling plate 554^a is a shoulder screw 686 which is threaded into the platform 522^a and which cooperates with the shoulder screw 680

in the guiding of the coupling plate together with the slide 664 and the gage 68^a as a unit lengthwise of the axis 98. The coupling plate 554^a has formed in it a recess 688 which extends lengthwise of the axis 98 and in which fits a flange of the feeler 520^a, said feeler being secured in different positions to the plate by a screw 690 passing through a slot 692 in the flange of the feeler and threaded into the coupling plate. It will thus be apparent that the feeler 520^a is movable in response to vertical movement of the table 60^a and in response to movement of the slide 664 lengthwise of the axis 98 and that the feeler 520^a may be adjusted lengthwise of the axis 98 with relation to the coupling plate 554^a in order initially to move the feeler into engagement with the toroidal face 536 of the pattern 534.

It will be apparent that as the table 60^a is raised and lowered in response to the action of the servo unit 81 controlled by the cam slide 86 the edge gage will be moved respectively to the left and right as viewed in Fig. 24 with relation to the table as the result of the movement of the cam roll 670 in the groove 658. Accordingly, the feeler 520 cooperating with the pattern 534 will cause the servo unit 558 to swing the cutter 64 and the pattern 534 about the axis 98 in response to the rise and fall of the table 60^a as well as in response to movement of the edge gage 68^a lengthwise of the axis 98, the construction and arrangement being such that during the concaving operation the cutter is swung into different operating positions about the axis 98 to form on the heel blank 42^a the cup or attaching face 46^a the land 88^a of which is of uniform width.

Having thus described my invention, what I claim as new and desire to secure by Letters Patent of the United States is:

1. A concaving machine comprising a support having a substantially planar face, a rotary cutter having peripheral cutting edges a locus of which extends beyond said face, means for moving and guiding a work piece in a predetermined path over said face of the support in traversing relation to the cutter to cause said work piece to be concaved, mechanism operated in timed relation to said means for effecting relative bodily movement of the cutter and the support to vary the amount of projection of the locus of the cutting edges of the cutter beyond said face, and mechanism responsive to said relative bodily movement of the cutter and the support for causing a bridging spread of the locus of the cutting edges of the cutter beyond said face to be approximately constant irrespective of the amount of projection of said locus beyond said face.

2. A concaving machine comprising a support having a substantially planar face, a rotary cutter having peripheral cutting edges a locus of which extends beyond said face, means for moving and guiding a work piece in a predetermined path over said face of the support in traversing relation to the cutter to cause said work piece to be concaved, mechanism operated in timed relation to said means for moving the support at approximately right angles to said face to vary the amount of projection of the locus of the cutting edges of the cutter beyond said face, and mechanism responsive to movement of said support for causing a bridging spread of the locus of the cutting edges of the cutter beyond said face to be approximately constant irrespective of the amount of projection of said locus beyond said face.

3. A concaving machine comprising a support having a substantially planar face, a rotary cutter having peripheral cutting edges a locus of which extends beyond said face, a gage positioned adjacent to said face of the support and to the cutter, power means for moving a work piece with an edge thereof in engagement with said gage over the face of the support in traversing relation to the cutting edges of the cutter to cause said work piece to be concaved, mechanism operated in timed relation to said power means for moving the support relatively to

the cutter at approximately right angles to said face to vary the amount of projection of the locus of the cutting edges of the cutter beyond said face, and mechanism responsive to movement of the support for causing a bridging spread of the locus of the cutting edges of the cutter beyond said face to be approximately constant and also for causing one end of said spread to be located at a constant distance from said gage irrespective of the amount of projection of said locus beyond said face.

4. A concaving machine comprising a support having a substantially planar face, a rotary cutter having peripheral cutting edges a locus of which extends beyond said face, a gage positioned adjacent to said face of the support and to the cutter, power means for moving a work piece with an edge thereof in engagement with said gage over the face of the support in traversing relation to the cutting edges of the cutter to cause said work piece to be concaved, mechanism operated in timed relation to said power means for effecting relative bodily movement of the cutter and the support at approximately right angles to said face of the support to vary the amount of projection of the locus of the cutting edges of the cutter beyond said face, and mechanism responsive to relative bodily movement of the cutter and the support for causing one end of a bridging spread of the locus of the cutting edges of the cutter beyond said face to be located at a constant distance from said gage irrespective of the amount of projection of the locus beyond said face.

5. In a concaving machine, a table having a face, a cutter rotatable about an axis and projecting beyond said face, means for moving a heel blank in a predetermined path over said face and past the cutter to concave said blank, mechanism operative in timed relation to said means for varying the position of the table in a direction disposed at substantially right angles to said face, and means operative in response to movement of said mechanism for swinging the cutter into different operating positions about an axis which lies in a general plane of rotation of the cutter and which is arranged generally parallel and in close proximity to the face of the table.

6. In a concaving machine, a work support having a face, a cutter which is rotatable about an axis and projects beyond said face and which has peripheral cutting edges included in a toroidal surface the centers of transverse curvature of which lie in a circle, means for moving a work piece over the face of the support and past the cutter to concave the work piece, means operative in timed relation to said first-named means for moving the support as a unit relatively to the cutter, and mechanism movable in timed relation to said second-named means for swinging the cutter into different angularly adjusted positions about an axis which is substantially parallel to said face of the table and which lies substantially in the plane of and is tangent to said circle.

7. In a concaving machine, a table having a face, a circular cutter extending through the table and projecting beyond said face, a gage positioned adjacent to said face of the table and to said cutter, a jack for clamping a work piece, means for sliding and rotating the jack to cause the work piece to slide and turn on said face of the table with an edge of the work piece slidingly engaging said gage whereby to cause said work piece to traverse the cutter to concave the work piece, mechanism for moving the table relatively to the cutter at approximately right angles to the face of the table to cause the cutter to project different distances beyond said face in accordance with the desired depth to which said work piece is to be concaved, mechanism for swinging the cutter about a fixed axis which is generally parallel and is located in close proximity to the face of the table and which lies in a general plane of rotation of the cutter, and means for operating said means and said mechanism in timed relation.

8. In a concaving machine, a table which has a face and has extending through it a slot terminating at said

face, a circular cutter extending through the slot and beyond said face of the table, means for rotating the cutter, means for moving a work piece in a predetermined path over said face of the table and past the cutter to concave said work piece, fluid-pressure actuated means operated in timed relation to said second-named means for moving the table bodily relatively to the cutter at approximately right angles to said face, and fluid-pressure actuated means operated in response to movement of the table for swinging the cutter relatively to the table into different angular operating positions about an axis which is substantially parallel to and is arranged in close proximity to said face and which lies in a general plane of rotation of the cutter.

9. In a concaving machine, a table having a face for supporting a work piece, a circular cutter which has peripheral cutting edges and is rotatable in a general plane, said face of the table having a slot through which said cutter extends with a portion thereof projecting beyond said face, a gage mounted upon said face of the table adjacent to the slot, power actuated means for effecting movement of the work piece in a predetermined path, which is controlled in part by said gage, over said face of the table whereby to cause said work piece to traverse the cutter, cam controlled means operated in timed relation to said power actuated means for effecting movement of the table at approximately right angles to its face to vary the extent of projection of the cutter beyond said face, and means responsive to movement of the table for swinging the cutter laterally of its general plane of rotation and for maintaining a constant cutter spread beyond said face of the table irrespective of the position of the table.

10. In a heel blank concaving machine, a table having a planar face for supporting a heel blank, a slot formed in said face, a gage arranged on the table adjacent to said slot, a rotary cutter which has peripheral cutting edges and which extends through the slot and projects beyond said face of the table, a holder, means for clamping a heel blank in the holder, means for forcing against the gage the rim of an upper end of said heel blank, which is clamped in the holder with said end in engagement with a face of the table, and for moving said blank past the cutter to concave the upper end of the blank, mechanism which is operated in timed relation to said means and effects movement of the table at substantially right angles to the supporting face of the table to vary the amount of projection of the cutter beyond said face, and means movable in timed relation to said first-named means and said mechanism for swinging the cutter about an axis which lies in a general plane of rotation of the cutter and which is arranged in parallel relation and close proximity to the face of the table whereby to maintain, irrespective of the position of the table and the distance the cutter projects beyond said face of the table, a substantially constant distance between said gage and adjacent points at which lines of maximum cutting depth of a locus of the cutting edges of the cutter intersect a plane in which said face of the table lies.

11. A concaving machine having, in combination, a table provided with a planar face for receiving a heel blank, a rotary cutter which has spaced peripheral cutting edges and projects beyond said face of the table, a gage positioned on the table and adjacent to the cutter, means for moving the heel blank, an upper end of which is in engagement with the table and an edge of said end of which is in engagement with the gage, in a closed path past the cutter to concave the upper end of said blank, mechanism operated in timed relation to said means for raising and lowering the table during the movement of the blank over said face of the table to vary the distance that the cutter projects beyond said face of the table and accordingly the depth of the concaving cut formed in the upper end of said blank, and means for causing during the concaving operation a locus of the cut-

ting edges of the cutter to intersect a plane of the face of the table at a constant distance from said gage irrespective of the elevation of the table.

12. In a concaving machine, a table having a work supporting face, a cutter which has peripheral cutting edges and which extends through the table and projects beyond said face, a gage which is positioned on the table and adjacent to the cutter, mechanism for moving a work piece guided in part by the table and by said gage in a predetermined path past the cutter, means operated in timed relation to said mechanism for moving the table relatively to the cutter at approximately right angles to said face to vary the distance the cutter projects beyond the face of the table whereby to vary the depth of cuts formed in the work piece by the cutter, means responsive to movement of the table for moving the gage relatively to the table, and means responsive to movement of the table and the gage relatively to the table for swinging the cutter about an axis which is arranged in parallel relation and adjacent to the face of the table and which is arranged approximately in a general plane of rotation of the cutter.

13. In a concaving machine, a table having a planar face, a rotary cutter which extends through the table and projects beyond said face and which has peripheral cutting edges lying in a toroidal surface centers of transverse curvature of which lie in a circle, said cutter being mounted for tilting movement about an axis which is parallel to the face of the table and which lies in the plane of and is tangent to said circle, a gage mounted on the table adjacent to the cutter, a holder for a heel blank, means for moving the holder in a closed path, for supporting said holder for yielding movement away from the gage and for causing said holder to cooperate with said gage and said table in the guiding of the blank past the cutter, means comprising a cam operated in timed relation to the holder, fluid pressure means for raising and lowering the table in response to movement of the cam, a pattern mounted for tilting movement with the cutter about said axis and having a toroidal surface, a feeler carried by the table and adapted to contact and to be contacted by said pattern to effect displacement of the pattern with relation to the cutter, and fluid-pressure means responsive to said displacement of said pattern for swinging the cutter into predetermined positions about said axis in response to movement of the table.

14. In a concaving machine, a table having a planar face, a carrier, a cutter which is mounted rotatably on the carrier and which extends through the table and projects beyond said face and which has peripheral cutting edges lying in a toroidal surface centers of transverse curvature of which lie in a circle, said cutter and said carrier being mounted for tilting movement about an axis which is parallel to the face of the table and which lies in the plane of and is tangent to said circle, a gage mounted on the table adjacent to the cutter, a holder for a heel blank, means for moving the holder in a closed path, for supporting said holder for yielding movement away from the gage and for causing the holder to cooperate with said gage and said table in the guiding of the blank past the cutter, means comprising a cam operated in timed relation to the holder, fluid pressure means for raising and lowering the table in response to movement of the cam, a pattern mounted on the carrier and having a toroidal surface, a feeler carried by the table and adapted to contact and to be contacted by said pattern to effect displacement of the pattern on the carrier, and fluid-pressure means responsive to displacement of said pattern on the carrier for swinging the cutter into predetermined positions about said axis in response to movement of the table.

15. In a concaving machine, a table having a planar face, a cutter which extends through the table and projects beyond said face and which has peripheral cutting edges lying in a toroidal surface centers of transverse

curvature of which lie in a circle, said cutter being mounted for tilting movement about an axis which is parallel to said face of the table and lies in the plane of and is tangent to said circle, a gage arranged on the table adjacent to the cutter, a holder for a heel blank, means which is yieldingly movable away from the gage and is adapted to move the holder in a closed path past the cutter, a slide, a cam carried by the slide, fluid pressure means operatively connected to said table, mechanism operatively connecting said means to said slide for moving the slide and accordingly the cam in one direction from starting to projected positions whereby to render said fluid pressure means active to cause the table to be moved at right angles to its face in timed relation to said holder, fluid pressure means for moving the slide and accordingly the cam in an opposite direction from their projected to their starting positions, means for disconnecting said slide from said mechanism to cause movement of the slide in said one direction to cease, and for rendering said second-named fluid pressure means active to move the slide to its starting position, means operated in timed relation to the slide for rendering said first-named fluid-pressure means inactive and accordingly the table fixed while the slide is moving back to its starting position, means operative in response to the movement of the slide back to its starting position for rendering said mechanism active to connect the slide to said first-named means and to render the first- and second-named fluid pressure means active and inactive respectively as the slide returns to its starting position, a pattern which has a toroidal surface, a feeler carried by the table and adapted to contact and to be contacted by said pattern to effect displacement of said pattern with relation to the table, and fluid pressure means responsive to said displacement of the pattern for tilting the cutter into predetermined positions about said axis.

16. In a concaving machine, a table having a planar face, a carrier, a cutter which is mounted rotatably on the carrier and extends through the table and which projects beyond said face and has peripheral cutting edges lying in a toroidal surface centers of transverse curvature of which lie in a circle, said cutter and said carrier being mounted for tilting movement about an axis which is parallel to said face of the table and lies in the plane of and is tangent to said circle, a gage arranged on the table adjacent to the cutter, a jack for a heel blank, means which is yieldingly movable away from the gage and is adapted to move the jack in a closed path past the cutter, a slide, a cam which is carried by and is movable into different initially adjusted positions on the slide, fluid pressure means operatively connected to said table, mechanism operatively connecting said first-named means to said slide for moving the slide and accordingly the cam in one direction from starting to projected positions whereby to render said fluid pressure means active to cause the table to be moved at right angles to its face in timed relation to the jack, fluid pressure means for moving the slide and accordingly the cam in an opposite direction from their projected to their starting positions, means for disconnecting said slide from said mechanism to cause movement of the slide in said one direction to cease, and for rendering said second-named fluid pressure means active to move the slide back to its starting position, means operated in timed relation to the slide for rendering said first-named fluid pressure means inactive and accordingly the table fixed while the slide is moving back to its starting position, means operative in response to the movement of the slide back to its starting position for rendering said mechanism active to connect the slide to said first-named means and to render the first- and second-named fluid pressure means active and inactive respectively as the slide returns to its starting position, a pattern which has a toroidal surface and is mounted on but is displaceable with relation to the carrier, a feeler carried by the table and adapted to contact and to be contacted

by said pattern to effect displacement of said pattern on the carrier, and fluid pressure means responsive to displacement of said pattern on the carrier for tilting the cutter into predetermined positions about said axis.

17. A concaving machine comprising a table having a planar face, a rotary cutter which extends through the table and projects beyond said face and which has spaced peripheral cutting edges lying in a toroidal surface centers of transverse curvature of which lie in a circle, a gage slidably mounted on the table and positioned adjacent to the cutter, a jack comprising a clamp for gripping a work piece which is in engagement with said face of the table, means for moving the jack in a closed path over the table and for cooperating with said gage and the table in the guiding of the work piece past the cutter to concave the work piece, means movable in timed relation to the jack for bodily moving the table at right angles to said face of the table whereby to vary the amount the cutter projects beyond said face, means movable in timed relation to the jack and the table for moving the gage into different operating positions on the table, and means operative in response to the movement of the table and the movement of the gage relatively to the table for swinging the cutter about an axis which is parallel to said face of the table and is tangent to and is arranged in a plane of said circle.

18. A concaving machine comprising a table having a planar face, a rotary cutter having cutting edges a locus of which extends through the table and beyond said face of the table, a gage slidably mounted on the table and positioned adjacent to the cutter, a jack comprising a clamp for gripping a work piece which is in engagement with said face of the table, means for moving the jack over the table in a closed path and for cooperating with said gage and the table in the guiding of the work piece past the cutter to concave said work piece, means movable in timed relation to the jack for bodily moving the table at right angles to its face whereby to vary the extent of projection of the locus of the cutting edges of the cutter beyond said face, means movable in timed relation to the jack and the table for moving the gage into different operating positions on the table, and means operative in response to the movement of the table and movement of the gage with relation to the table for maintaining, irrespective of the position of the table and the gage on the table, a constant distance between the gage and an intersection of a plane of the table and a line of maximum cutting depth of the locus of the cutting edges of the cutter.

19. A heel blank concaving machine comprising a table having a planar face, a rotary cutter which extends through the table and projects beyond said face of the table and which has skewed peripheral cutting edges lying in a toroidal surface centers of curvature of which lie in a circle, a gage positioned adjacent to the table and to the cutter, a jack, a clamp for securing a heel blank in the jack, mechanism which is bodily yieldable away from said gage and is adapted to effect movement of translation and rotation of the jack to move the heel blank over said face of the table with a rim of an upper end of said blank in sliding engagement with the gage whereby to cause the upper end of the blank to traverse the cutter, means for raising and lowering the table in timed relation to said movement of the jack to vary the amount that the cutter projects above the face of the table during the traversing of the heel blank past the cutter, and means responsive to movement of the table for swinging the cutter about an axis which is parallel to said face of the table and which lies approximately in the plane of and is tangent to said circle.

20. A heel blank concaving machine comprising a table having a planar face, a rotary cutter which extends through the table and projects beyond the face of the table and which has skewed peripheral cutting edges lying in a toroidal surface centers of transverse curvature of which

lie in a circle, a gage positioned adjacent to the table and to the cutter, a jack, a clamp for securing a heel blank in the jack, mechanism which is bodily yieldable away from the gage and is adapted to effect movement of translation and rotation of the jack to move the heel blank over said face of the table with a rim of an upper end of said blank in sliding relation to the gage whereby to cause the upper end of the blank to traverse the cutter, means for raising and lowering the table in timed relation with said movement of the jack to vary the amount that the cutter projects above the face of the table during the traversing of the heel blank past the cutter, and means responsive to movement of the table for swinging the cutter about an axis which is parallel to said face of the table and which lies approximately in the plane of and is tangent to said circle, said mechanism comprising a pair of telescopically arranged parts and resilient means for constantly urging one of said parts toward the jack in order constantly to urge said jack toward the table whereby to allow the jack to be raised and lowered with the table during the concaving of the heel blank.

21. In a concaving machine, a table having a planar face, a carrier mounted for movement about an axis which is parallel to said planar face, a cutter which is rotatably mounted on the carrier and which extends through the table and which projects beyond said face of the table and has peripheral edges lying in a toroidal surface centers of transverse curvature of which lie in a circle, and means for initially positioning the cutter upon the carrier with said circle arranged in and tangent to said axis.

22. In a concaving machine, a table having a planar face, a carrier which comprises two parts and is mounted for movement about an axis arranged in parallel relation to said planar face of the table, a shaft which is rotatably mounted on one part of said carrier, a cutter which is secured to the shaft and extends through the table and which projects beyond said face of the table and has peripheral edges lying in a toroidal surface centers of transverse curvature of which lie in a circle, a motor which has a shaft and is mounted on another part of the carrier, and driving means between the motor and the cutter shafts, said cutter being adjustable on its shaft to move a plane of said circle into a position in which it includes said axis and said one part of the carrier being adjustable relatively to said other part to move said circle into tangential relation to said axis.

23. In a concaving machine, a table having a planar face, a carrier journaled for movement about a fixed axis arranged substantially parallel and in close proximity to said face of the table, a rotary cutter which has peripheral cutting edges and is rotatably mounted on the carrier with a plane of rotation thereof arranged substantially in said axis and which extends through the table and projects above said face of the table, a gage positioned adjacent to said face of the table and to the cutter, mechanism for guiding a work piece with an edge thereof in engagement with the gage over said face of the table with traversing action past the cutter, means for raising and lowering the table in timed relation to said mechanism, a pattern which is yieldingly mounted on said carrier and has a surface similar to a locus of the cutting edges of the cutter, resilient means for moving the pattern to one position on the carrier, a feeler secured to the table and adapted to engage and to be engaged by said surface of the pattern to regulate movement of the pattern on the carrier in accordance with the movement of the table, a servo unit, and means for operatively connecting the servo unit to the pattern and the carrier to cause the carrier and accordingly the cutter to be swung about said axis in timed relation to the table.

24. In a concaving machine, a table having a planar face, a carrier journaled for movement about a fixed axis arranged substantially parallel and in close proximity to said face of the table, a rotary cutter which has peripheral cutting edges and is rotatably mounted on the carrier with

a plane of rotation thereof arranged substantially in said axis and which extends through the table and projects beyond said face of the table, a gage positioned adjacent to said face of the table and to the cutter, power operated mechanism for guiding a work piece with an edge thereof in engagement with the gage over said face of the table and with traversing action past the cutter, a slide movable in timed relation to said mechanism, a cam carried by and adjustable with relation to the slide, a servo unit operative in response to movement of the cam for raising and lowering the table, a pattern which is yieldingly mounted on said carrier and has a surface similar to a locus of the cutting edges of the cutter, resilient means for moving the pattern to one position on the carrier, a feeler secured to the table and adapted to engage and to be engaged by said surface of the pattern to regulate movement of the pattern on the carrier in accordance with the movement of the table, a servo unit, and means for operatively connecting the servo unit to said pattern and to said carrier to cause the carrier and accordingly the cutter to be swung about said axis in timed relation to the table.

25. In a concaving machine, a table having a planar face, a carrier journaled for movement about a fixed axis arranged substantially parallel and in close proximity to said face of the table, a rotary cutter which has peripheral cutting edges and is rotatably mounted on the carrier and which extends through the table and projects above the face of the table, a motor which is mounted on the carrier and is operatively connected to the cutter, a gage carried by the table, means for positioning the gage initially in different positions on the table and adjacent to the cutter, power-operated mechanism for guiding a work piece with an edge thereof in engagement with the gage over said face of the table and with traversing action past the cutter, means for raising and lowering the table in timed relation to said mechanism, a pattern which is yieldingly mounted on said carrier and has a surface similar to a locus of the cutting edges of the cutter, resilient means for moving the pattern in one direction on the carrier, a feeler carried by the table and initially adjustable into different operating positions upon the table, said feeler being adapted to engage and be engaged by said surface of the pattern to regulate movement of the pattern on the carrier in accordance with the movement of the table, a servo unit, and means for operatively connecting the servo unit to the pattern and to the carrier to cause the carrier and accordingly the cutter to be swung about said axis in timed relation to the table.

26. In a concaving machine, a table having a planar face, a carrier journaled for movement about a fixed axis arranged substantially in parallel relation and in close proximity to said face of the table, a cutter which is rotatably mounted upon the carrier, extends through the table and projects beyond said face of the table and has cutting edges lying in a toroidal surface centers of transverse curvature of which lie in a circle which is tangent to said axis and in a plane in which said axis lies, a gage positioned adjacent to said face of the table and to the cutter, mechanism for guiding a work piece with an edge thereof in engagement with said gage over said face of the table and with traversing action past the cutter, a slide, means for moving the slide in timed relation to said mechanism, a multipart cam mounted upon the slide, fluid-pressure means which is operated in response to movement of the cam and is adapted to displace the table in directions disposed at right angles to said face of the table, means for initially moving the multipart cam into different adjusted positions on the slide in accordance with the desired displacement of the table during different portions of travel of the work piece past the cutter, a pattern which is yieldingly mounted on the carrier and has a toroidal surface substantially identical with the toroidal surface in which the cutter edges of the cutter lie, resilient means for constantly urging the pattern in one direction on

70
75

the carrier, a feeler secured to the table and adapted to engage and to be engaged by the surface of the pattern to cause said pattern to be moved on the carrier in opposite directions in accordance with the direction of movement of the table, a servo unit, and means which operatively connects the servo unit to said pattern and to the carrier to cause the carrier and accordingly the cutter to be swung about said axis in timed relation to the table.

27. In a heel blank concaving machine, a table having a planar face, a rotary cutter extending through the table and projecting beyond said face of the table, a gage which is arranged adjacent to said face of the table and to the cutter and which has a flat surface, mechanism for moving a heel blank in a predetermined path over said face of the table with an edge of an upper end thereof in engagement with said flat surface of the gage to move said blank with traversing action past the cutter, said cutter having peripheral cutting edges a common locus of rotation of which for any one setting of the cutter includes a line of maximum cutting depth bridging said face of the table and intersecting said face at two points, means operative in timed relation to said mechanism for moving the table at approximately right angles to its face to vary the distance of projection of the locus of the cutting edges of the cutter beyond said face, and means for swinging the cutter in timed relation to the table to cause the points of intersection of lines of maximum depth for different angles of swing of the cutter to intersect a plane of the face of the table along lines respectively which are approximately parallel to said flat surface of the gage.

28. In a concaving machine, a support having a flat face, a rotary cutter projecting beyond said face of the support, a gage arranged adjacent to the cutter and to the face of the support, a jack, means for clamping a work piece in the jack with a surface of said work piece overlying the support, means for moving the jack and accordingly the work piece in a closed path over the face of the support with an edge of the work piece in sliding relation to the gage past the cutter to concave an inner portion of said surface of the work piece, means for mounting the jack for yielding movement away from said gage to permit the jack to move away from the gage to permit the edge of the work piece to be moved slidingly along the gage, means for moving the support relatively to the cutter at right angles to the face of the support in timed relation to said first-named means to vary the distance which the cutter projects beyond said face and accordingly to vary the depth of the concavity formed in said surface of the work piece, and means for swinging the cutter in timed relation to the support during the concaving operation to form between an edge of said surface of the work piece and the concavity formed in said surface by the cutter an uncut land of uniform width irrespective of the amount the cutter projects beyond said face of the support.

29. In a heel blank concaving machine, a table having a planar face, a rotary cutter extending through the table and projecting beyond said face of the table, a gage which is arranged adjacent to said face of the table and to the cutter and which has a flat surface, mechanism for moving a heel blank in a predetermined path over said face of the table with an edge of an upper end thereof in engagement with said flat surface of the gage to move said blank with traversing action past the cutter, said cutter having peripheral cutting edges a common locus of rotation of which for any one setting of the cutter includes a line of maximum cutting depth bridging said face of the table and intersecting said table at two points, means operative in timed relation to said mechanism for moving the table at approximately right angles to its face to vary the distance of projection of the locus of the cutting edges of the cutter beyond said face, means responsive to movement of the table for moving the gage relatively to the table, and means for swinging the cutter in opposite directions over the face of the table in response to displacement of the table and to displacement of the gage

with relation to the table to cause said points of intersection of the lines of maximum cutting depth of different angles of swing of the cutter to intersect a plane of said face of the table along adjacent and remote diverging lines while maintaining constant distance between the flat surface of the gage and a point on said adjacent line being intersected.

30. In a concaving machine, a support having a flat face, a rotary cutter projecting beyond said face of the support, a gage arranged adjacent to the cutter and to the face of the support, a jack, means for clamping a work piece in the jack with a surface of the work piece overlying the support, means for moving the jack and accordingly the work piece past the cutter in a closed path over the face of the support with an edge of the work piece in sliding relation to the gage to concave an inner portion of said surface of the work piece, means for mounting the jack for yielding movement away from the gage to permit the edge of the work piece to be moved slidingly along the gage, means for moving the support relatively to the cutter at right angles to the face of the support in timed relation to said first-named means to vary the distance which the cutter projects beyond said face and accordingly to vary the depth of the concavity formed in said face of the work piece, and means for swinging the cutter in timed relation to the support during the concaving operation to form between an edge of said surface of the work piece and the concavity formed in said surface by the cutter an uncut land of uniform width irrespective of the amount the cutter projects beyond said face of the support.

31. In a concaving machine comprising a support having a substantially planar face, a rotary cutter having peripheral cutting edges a locus of which extends beyond said face of the support, a gage positioned adjacent to said face of the support and to the cutter, means for effecting movement of the work piece with an edge thereof in engagement with said gage in a predetermined path over said face of the support in traversing relation to said edges of the cutter to cause a surface of the work piece to be concaved, mechanism operated in timed relation to said means for effecting relative translatory movement of the cutter and the support at approximately right angles to said face of the support to vary the amount of projection of the locus of the cutting edges of the cutter beyond said face of the support, and mechanism responsive to said relative translatory movement of the cutter and the support for maintaining a constant distance between the gage and an intersection of the plane of the table and the locus of the cutting edges of the cutter.

32. A concaving machine comprising a support having a substantially planar face, a rotary cutter having peripheral cutting edges the locus of which extends beyond said face of the support, a gage, means for moving a work piece with an edge thereof in engagement with the gage in a predetermined path over said face of the support in traversing relation to the cutting edges of the cutter to cause said work piece to be concaved, mechanism operated in timed relation to said means for moving the support at approximately right angles to said face of the support to vary the amount of projection of the locus of the cutting edges of the cutter beyond said face, and mechanism responsive to movement of said support for maintaining, during the relative bodily movement of the cutter and the support and irrespective of the amount of the projection of said locus above the face of the support, a constant spread of the locus over said face and a uniform distance between the gage and an intersection of the plane of the support and the locus of the cutting edges of the cutter.

33. In a concaving machine, a table having a work supporting face, a cutter which has peripheral cutting edges and which extends through the table and projects beyond said face, a gage which is positioned on the table

31

adjacent to the cutter; mechanism for moving the work piece guided in part by said gage in a closed path past the cutter, means operated in timed relation to said mechanism for moving the table relatively to the cutter at right angles to said face to vary the distance the cutter projects beyond said face of the table whereby to vary the depth of the cuts formed in the work piece by the cutter, means responsive to movement of the table for moving the gage relatively to the table and to the cutter, and means for maintaining a uniform distance between the gage and an intersection of the plane of the table and a locus of the cutting edges of the cutter and for increasing and decreasing the spread of said locus over said face in response to the combined movements of the table with relation to the cutter at right angles to said face of the table and of the gage with relation to the table and to the cutter.

34. A concaving machine comprising a support having a substantially planar face, a rotary cutter having peripheral cutting edges a locus of which extends beyond said

10

5

15

16

20

32

face, means for moving and guiding a work piece in a predetermined path over said face of the support in traversing relation to the cutting edges of the cutter to cause said work piece to be concaved, mechanism operated in timed relation to said means for effecting relative bodily movement of the cutter and the support at approximately right angles to said face to vary the projection of the locus of the cutting edges beyond said face, a gage movable toward and away from the cutter and adapted to cooperate with said means in the guiding of the work piece over said face, and means responsive to relative bodily movement of the cutter and the support and to movement of the gage on the support for maintaining a uniform distance between said gage and an adjacent intersection of a plane of the face of the support and a locus of the cutting edge of the cutter during the relative bodily movement of the cutter and the support and during movement of the gage upon the support.
